SWEATBAND

Application filed May 26, 1928. Serial No. 280,880.

Our present invention relates to the manufacture of hats, and more particularly to an improved sweat band and process of making the same therefor.

5 As previously manufactured, the sweat bands were made of a relatively soft material, such as leather, which is porous, and therefore the action of the perspiration destroys the life of the material and also allows the perspiration to percolate therethrough and saturate and discolor the material of the hat itself.

We propose to obviate the objections above noted and use a sweat band of impervious material. In utilizing such material, however, a difficulty was encountered in that the material was quite stiff and unyielding and, therefore, difficult to work. Modern sweat bands are provided with a knurling along 20 the top or open edge thereof and also we have proposed in addition to the knurling, to fold up a portion of the sweat band and form thereby what is practically a reservoir to catch and retain the perspiration and in 25 order that the perspiration may be removed from such reservoir, we place in such reservoir a lining of absorbent material such as blotting paper. In carrying out this idea in practical form it was found that the resilient 30 material was so unyielding as to render it practically impossible to fold the material along one edge to form a reservoir simultaneously with fitting the same into the hat structure and, therefore, we devised a method 35 of perforating the sweat band and form the knurling along one edge and fold up the opposite edge, simultaneously. We find it advantageous, of course, to provide the structure of the sweat band with a plurality of 40 perforations through which the perspiration may percolate.

The object of our invention, therefore, is an improved novel sweat band for hats and the like.

45 In the accompanying drawings illustrating a preferred embodiment of our invention,

Fig. 1 is a perspective view of a sweat band showing portions broken away to disclose the 50 construction, and

Fig. 2 is a section through the hat showing the sweat band attached thereto.

Referring to the drawings, 10 designates a strip of material of an impervious nature, such as treated leather, fibreboard, artificial leather or the like, of suitable width and thickness and of a length sufficient to encircle the inner circumference of the crown of a hat 11. Along one edge there is formed a knurling 12 which acts to stiffen the same and also to slightly reduce the diameter of the sweat band formed thereby so as to allow the sweat band to more closely engage with the head of the wearer of the hat 11. Heretofore it was usual to form the knurling prior to the insertion of the sweat band 10 in the hat structure 11 and it was attempted, therefore, to fold the edge of the sweat band 10 opposite the knurling 10 upward, as indicated at 13. The parallelly arranged portions 10 and 13, therefore, form a reservoir in which fits the lower edge of a sheet of absorbent material 14. Because of the character of the material 10, which is of an impervious nature, it was found exceedingly difficult and practically impossible to make a smooth job and therefore, we place the knurling 12 and fold the portion 13 into position at one and the same time and by a machine suitable for this purpose. Afterwards, therefore, the practically completed sweat band 10 is sewn to the hat structure 11 by stitching 15. The absorbent material 14 may be of blotting paper, felt, or any other suitable material that is desired and being easily removable, offensive odors 55 from perspiration are avoided and also the material of the hat 11 is protected and is not subject to discoloration, as has been heretofore the case. The material of the sweat band 10 being impervious, it is essential that there be provided a plurality of perforations 16 of any suitable size and arranged in any suitable manner, it being desirable, however, that the lower perforation 16 be not too close to the bottom of the reservoir formed by the elements 10 and 13. 60

Having thus described our invention, what we claim as new is:

An improved sweat band for hats and the like, comprising a strip of impervious mate- 65

rial of suitable width and length, a line of knurling adjacent to one edge thereof, a portion of the opposite edge being folded back upon itself parallel with the remaining portion and to thereby form a reservoir, a plurality of perforations extending through the main portion of the sweat band into said reservoir, and a filler of absorbent material in said reservoir.

10 In testimony whereof, we have signed our names to this specification.

A. WALDO ROCKWOOD.
CLAUDE A. MILBERY.
